Des. 204,385

Patented Apr. 12, 1966

204,385

MAGNETIC TAPE UNIT OR SIMILAR ARTICLE

Carl C. Roecks, Phoenix, Ariz., assignor to General
Electric Company, a corporation of New York

Filed May 27, 1965, Ser. No. 85,481

Term of patent 14 years

(Cl. D26—5)

The single figure is an isometric view of a magnetic tape unit, or similar article, showing my new design.

The characteristic features of my new design are shown in solid lines and reside in the two side-by-side, vertically mounted vacuum columns disposed to one side, combined with a covering door for the tape processing head assembly and tape driving means located above the two vacuum columns and a fixed tape reel and a spindle for a removable tape reel positioned to the side of the vacuum columns and covering door.

The tape and lower tape reel, shown in broken lines, are for purposes of illustration only.

I claim:

The ornamental design for a magnetic tape unit, or similar article, as shown and described.
